10 Claims. (Cl. 164—49)

This invention relates to apparatus for chopping a continuous web of material into sheets of a given length automatically in response to, and in accordance with, signal marks spaced longitudinally of the web.

It is common practice in the photographic art to make a plurality of photographic prints in succession on a continuous web of light-sensitive paper and roll them up for later processing in strip form. After processing these prints are then run through a chopping apparatus which chops the web into individual prints. In order to render this chopping action fast and automatic, signal marks have been placed on the strip of prints at the time of printing, and in particular spaced relation to the print areas, which serve to control the feed of the strip of prints to the chopper and the actuation of the chopper to sever the prints from the strip. It has even been suggested that these signal marks be electrically conducting marks which serve to bridge a pair of spaced contacts in an electric control circuit to stop the paper feed and operate the chopper at a given time. Usually reciprocal chopping apparatus is used for this purpose and the feed of the strip of prints to the knife is intermittent and direct from the supply roll.

We have found that known print chopping apparatus of this type have been unsatisfactory for several reasons. First, since the prints were intermittently fed to the chopping station directly from a supply roll, the load on the paper was continually changing, primarily due to change in the size of the supply roll, with the result that the feed of paper to the chopper varied from time to time. This results in there being a variation in the length of successive prints which means that the margins on the same prints and on successive prints will vary in width. This not only spoils the appearance of the individual prints, but a variation in length from print to print is very undesirable where the prints are to be ultimately bound in stacked relation in an album for return to the customer as is common practice in the photofinishing business today. Furthermore, a variation in length of paper feed from print to print can be cumulative so that eventually a print may be chopped through its picture area. This variation in length of paper feed is particularly annoying when prints of different size are intermixed on a single strip of paper and, hence, require different lengths of feed in the chopper. In addition, this problem of uniform or accurate feed of the paper to the chopper is greatly aggravated when an attempt is made to operate the chopper at high speed, for then any fluctuation in load against which the intermittent paper feed must work becomes quite critical.

Therefore, the primary object of the present invention is to provide an apparatus for severing a continuous web into sheets of a given length in response to signal marks spaced along the length of the web wherein the web is

2

intermittently advanced to a reciprocal chopping device by a feeding means which insures the intermittent feeding means acting against a constant load at all times with the result that the length of the cut sheets corresponds accurately with the signal mark spacing on the web.

Another object is to provide an apparatus for chopping a strip of photographic prints up into individual prints in accordance with electrical conducting marks spaced along the strip of prints which comprises constantly feeding the strip of prints from a supply into a loop and intermittently from the loop across a signal mark detector station and to the cutter. The passage of a signal mark on the paper over the detector station causes cessation of the intermittent feeding means and operation of the cutter to chop a print from the strip while the same is stationary.

A further object is to provide a print chopping apparatus of the type set forth in which the intermittent feed comprises a constantly-driven rubber-covered roller across which the strip is fed and onto which the strip is periodically pressed by a roller in order to advance the same. The drive is effected and broken by periodically pressing the strip in contact with this rubber-covered drive roller and releasing the pressure, respectively, in response to a conducting mark on the paper closing an open switch in a control circuit of the device.

And another object is to provide a print-chopping apparatus of the type described wherein the intermittent feeding means will not advance the strip unless the free loop in front thereof is large enough, and as a result of which there is a constant load on the intermittent feeding means each time it is operated.

Still another object is to provide a chopping apparatus of the type described wherein the means for constantly feeding the strip to the loop is stopped in the event the loop gets too large or disappears, and which conditions might be caused by the strip being jammed between the intermittent feed and the chopper or by the supply of strip becoming exhausted or the strip becoming broken.

A further object of the invention is to provide a chopper of the type described wherein the intermittent feeding means is paralyzed when said loop becomes too small and is maintained in such condition until the loop reaches a given minimum size. The minimum size of loop necessary to the operation of the device is determined by the length of strip which is to be advanced for the successive chopping operation.

Still another object of this invention is to provide a brake for the strip between the loop and intermittent feeding means which is adapted to frictionally hold the strip against movement when the intermittent feed is not operating and to assist build-up of the loop, and which brake is intermittently applied and released at the same time the intermittent feed is stopped and started, respectively.

The novel features that we consider characteristic of our invention are set forth with particularity in the appended claims. The invention itself, however, both as to its organization and its methods of operation, together with additional objects and advantages thereof, will best be understood from the following description when read in connection with the accompanying drawings in which:

Fig. 1 is a top plan view, with certain parts of the enclosing casings broken away, of a chopping apparatus constructed according to a preferred embodiment of the present invention.

Fig. 2 is a longitudinal sectional view of the chopping apparatus shown in Fig. 1.

Fig. 3 is a transverse sectional view taken substantially on line 3—3 of Fig. 2, but on an enlarged scale,

Fig. 4 is a transverse sectional view taken substantially on line 4—4 of Fig. 2,

Fig. 5 is a sectional view taken substantially on line 5—5 of Fig. 4, and showing the feeler arm engaging a loop of normal size,

Fig. 6 is a sectional view taken substantially on line 5—5 of Fig. 4 and showing the feeler arm in the position it assumes when the loop becomes too small (full-line position) and the position it assumes when the loop becomes too large (dotted-line position).

Fig. 7 is a schematic view showing what a strip of prints might look like which this chopping apparatus is to handle, and indicating how the conducting marks thereon connect two spaced contacts in the control circuit of the cutter as the strip passes the detector station in order to stop the intermittent feed and actuate the chopper, and

Fig. 8 is a schematic wiring diagram of the power and control circuit of this chopping apparatus.

Fig. 9 is a schematic view showing another modification of the intermittent web feeding means and web braking means wherein two solenoids instead of one are used.

Like reference characters refer to corresponding parts throughout the drawings.

Briefly, this chopping apparatus is primarily intended for automatically chopping photographic prints from a roll of processed photographic paper on which prints have been made on a photographic printer. During the printing operation, a marking device associated with the printer puts an accurately located electrical conducting mark on the back of each print as it is printed on the printer. After the roll of prints is processed, the strip of prints is run through this chopping device which chops the roll into individual prints in accordance with, and in response to, the conducting marks placed on the strip of prints.

The roll of processed prints is placed on a supply spindle of the cutter and the strip is fed from there through a pair of constantly-driven metering rolls into a free loop, then through an intermittent feeding and braking mechanism which periodically feeds it from the free loop over a pick-up or detector station and then between the knives of the cutter. The passage of a conducting mark on the strip over the pick-up or detector completes a control circuit which stops the intermittent feed and applies the brake to the strip in front of the loop and actuates the knives to chop off a print. Just as soon as the cutter completes its cutting stroke, the control circuit is reset to again start the intermittent feed of the strip. When the next conducting mark on the strip of prints passes the pick-up or detector station, the intermittent feed is again stopped and the knives actuated again to cut the next print, etc.

One of the most important features of this chopping apparatus which distinguishes it from, and overcomes a decided disadvantage of, similar known devices is the fact that the intermittent feed of the strip to the cutter pulls the strip from a free loop rather than directly from the supply roll. This results in the intermittent feeding mechanism working against a load which is substantially constant from print to print throughout the entire length of the strip to be chopped into sheets, rather than against a load which varies from time to time due to a changing diameter of supply roll, difference of frictional drag, etc. as in known chopping apparatus. This results in obtaining a plurality of prints which are accurately cut to a given length and each print having uniform margins so that they can be bound in albums for return to the customer and still present a neat and uniform appearance.

Our present chopping apparatus also includes means for paralyzing the intermittent feeding means when the free loop becomes so small as to contain a length of strip

which is less than that required for a given feeding operation and until the loop returns to sufficient size. It also includes means for stopping the continuous feed when the loop gets too large as might be the case if the strip jams in front of the intermittent feed at the chopper, or becomes completely lost, as would be the case if the supply of strip runs out or the strip breaks between the continuous and intermittent feeds. Means are also provided for selectively shutting off the power drive for the strip of prints so that they can be manually fed to the chopper if so desired.

Before describing this print-chopping apparatus and its function, it may be well to describe what a strip of photographic prints that it is to handle might look like. In Fig. 7 a portion of a strip of processed photographic prints is shown having signal or conducting marks spaced therewith along to control the chopping operation. This strip of prints comprises a web of paper W, bearing printed areas P spaced therewith and separated by clear areas A. Usually the width of the web W equals one dimension, usually the shorter, of a print, whereas the long dimension of the print extends longitudinally of the web. When the prints are chopped from the web, the cut is made through the clear areas A so as to leave a given, and uniform, white margin on one, or both, ends of each print. When the prints are made on the photographic printer, a signal of some form, preferably an electrical conducting mark M is made on the back of each print. This mark is accurately located with respect to the leading edge of its respective print in order to control the point at which the clear areas A are chopped so as to leave a given margin on the print. For instance, if the clear areas A are to be cut on the dotted line shown in Fig. 7 the distance between this line and the mark M on the following print is accurately controlled so as to be equal from print to print along the strip. This conducting mark on the back of the prints may be made with a pen using a special carbon ink, or may be made with a pencil having a special graphite lead. The pencil is preferred since there is less tendency for the mark to be smudged, there is no danger of spilling ink about the printer, and the pencil mark withstands the film processing baths very well. For that matter, so far as the present invention is concerned, the conducting marks M can be replaced by any form of suitable signal mark which can be applied to the strip of prints and serve to actuate a control circuit in the manner set forth, e. g., perforations, dark marks controlling photo cells, etc. As shown, these marks are preferably put on the roll at certain points so as to bridge and electrically connect two spaced pick-up or detector contacts C, C', shown diagrammatically in Fig. 7, which form a part of the chopper control and constitute a normally open switch in the control circuit of the chopping apparatus, as will be fully described hereinafter.

Referring now to the drawings, wherein a preferred embodiment of the present invention is shown, the chopping apparatus comprises a housing 10 consisting of a bottom 11, having rubber feet 12 for supporting the apparatus on a table top, and front and rear walls 13 and 14, respectively. As clearly indicated in Fig. 3, the rear wall 14 is slightly higher than the front wall 13 so that a top plate 15 joining the two, and forming a supporting surface for the web to be chopped, is inclined downwardly toward the front of the apparatus. Having the top plate 15 of the apparatus tipped forwardly facilitates operating the device from a sitting position in that the web and its path can be readily viewed.

A supply roll of processed prints, not shown, is slipped onto a supply spindle 16 rotatably mounted at the left-hand end of the apparatus, looking at the same from the front, said spindle being inclined the same as the top plate of the apparatus so that the roll of prints is held against a flange 17 by gravity, see Fig. 3. To accommodate strips of prints of different width, the flange 17

may be adjusted between a plurality of given positions axially of the spindle by means of adjusting knob 18 extending from the front of the device. The web W is led from the supply roll, picture side up, first over a constantly-driven rubber-covered metering roller 19 whose periphery extends through a slot 20 in the top plate 15 to, or slightly above, the surface of the plate 15. The web W is held in driving engagement with the metering roll 19 by a freely rotating presser roller 21 disposed directly above the metering roller 19, and journaled on a shaft 22 eccentrically mounted in brackets 23 mounted on, and extending upwardly from, the top plate 15 so that the pressure between the metering roller 19 and presser roller 21 can be varied to accommodate different thicknesses of paper. It will be noticed that rubber-covered metering roller 19 is relatively narrow and located substantially on the center line of the web path, see Fig. 1, whereas presser roller 21 is long enough to engage the full width of the web so as to help guide the same.

From the metering roller 19 the web W is fed into a free loop L and thence under a guide bar 25 pinned at one end to one end of an arm 26 rotatably mounted at the other end on the shaft of the presser roll 21. The weight of this guide bar and its arm normally presses the web to the top of the table at the leaving side of the loop L, and is frictionally held in this position by a spring-pressed ball 27 engaging a notch 28 in the pivoted end of the arm. For manual feeding of the web, as will be described hereinafter, or for threading purposes, the guide bar may be swung to a raised position, shown in dotted lines in Fig. 5, where it is frictionally held by the spring-pressed ball 27 engaging a second notch 29 in the pivoted end of the arm spaced approximately 90° from said first-mentioned notch 27. For guiding the sheet sidewise, guide bar 25 has a pair of flanges 30 rotatably and slidably mounted thereon. The flanges are held in different adjusted positions axially of the bar, for the purpose of accommodating different width webs, by virtue of the flanges extending into one or another of a plurality of grooves 31 in the top plate 15, the set of grooves for each flange being spaced from one another transversely of the web path, see Figs. 2, 3 and 4.

After passing the guide bar 25 the web W moves along the top plate 15 to the intermittent feeding mechanism which is adapted to pull the web from the loop L and feed a given length thereof through the chopping mechanism. This intermittent feeding mechanism comprises a constantly-driven rubber-covered indexing roller 32 which is mounted below the top plate 15 and extends upwardly through a slot 33 therein to frictionally engage the back of the web W. As clearly shown in Figs. 3 and 4, this indexing roller 32 is similar in shape, size and mounting to metering roller 19, and is carried by a shaft 34 journaled at one end in bearing housing 35 fixed to the underside of the top plate 15 and extending through an opening 36 in the rear wall 14 of the housing 10 where it is journaled in a bearing 37 carried by a casting 38 fixed to the top plate 15, see Fig. 3.

In order to intermittently feed the film, the web W must be pressed down against indexing roller 32 by a polished metal presser roller 39, the roller being freely rotatable and its surface polished so as not to injure the faces of the prints on the web. When this roller is raised from the indexing roller, the frictional engagement between indexing roller 32 and the web is not sufficient to feed the web. To effect selective movement of presser roller 39 to and from the indexing roller 32, presser roller is rotatably mounted on one end of an arm 40 which is pivoted intermediate its ends on the eccentric portion 41 of a crank arm 42 journaled in a bearing housing fixed to the top of casting 38. The other end of the arm 40 terminates in a rubber pressure foot 43 which is adapted to be moved down into engagement with the web and press it against the top plate 15 when the arm 40 is

pivoted counterclockwise to raise the presser roller from the indexing roller to stop the paper feed, and is adapted to be moved away from the web when the arm 40 is moved in a clockwise direction to move the presser roller into engagement with the web and cause the intermittent feed to operate. Accordingly, when the intermittent feed is interrupted, the pressure foot 43 is simultaneously moved to its web-holding position to both prevent the indexing roller 32 from unintentionally feeding the web due to its slight frictional engagement therewith and to hold the web in front of the loop L so that it cannot be advanced by the action of the constantly-operating metering roll 19 feeding the web forward to restore the loop. After the chopper has severed the length of web fed thereto by the previous intermittent feeding action, the arm 40 is pivoted clockwise to raise the pressure foot 43 and drop presser roller 39 down into engagement with the web to advance another length of web. The arm 40 is moved to its feed interrupting position, or counterclockwise, by energization of a solenoid 44, see Figs. 2 and 3 whose armature is pivoted at 45 to a link 46 connected to the eccentric portion 41 of the crank 42. A tension spring 47 connected at one end to link 46 and at the other end to a pin 48 fixed to the underside of top plate 15 normally acts in opposition to the solenoid and tends to swing arm 40 in a clockwise direction or to a position where the presser roller 39 is moved to its web feeding position, as shown in Fig. 2. It will be readily appreciated that instead of mounting the presser roll 39 and presser foot 43 on opposite ends of the pivoted arm 40 so that they can be simultaneously operated by a single solenoid 44, each of these members could be mounted on a separate pivoted arm and each operated by its own solenoid connected in a circuit so as to be energized simultaneously, as shown in Fig. 9. In this embodiment the presser foot 43' is fastened to the end of a lever 40' pivoted to the frame at point 41'. This foot is normally raised from the web foot by a tension spring 200 connected at one end to a pin 201 on the other end of the lever. The plunger 202 of a solenoid is connected to pin 201 by a bail 204 so that when the solenoid coil 203 is energized the plunger is pulled up to apply the brake to the web. The presser roll 39' is carried on one end of a lever 207 pivoted at 208. This roll is normally urged to its operative position relative to feed roll 32 by a tension spring 209 and is adapted to be moved to its inoperative position by the plunger 210 of a solenoid when the coil 211 thereof is energized. It will be appreciated that the two solenoid coils should be connected in series in the same power circuit so that they will be simultaneously energized when said power circuit is completed upon closure of a switch actuated by the signal marks on the web reaching a given point.

The drive for the metering roller 19 and the indexing roller 32, and in fact for all power-actuated parts of the device, emanates from a motor 50, contained within the housing 10, and whose shaft 51 drives a gear reducing unit 52, the power shaft 53 of which extends transversely of the housing, see Figs. 2 and 3. A gear 54, fixed to power shaft 53 engages and drives the larger of a pair of coaxial idler gears 55 and 56, the smaller of which in turn drives a second pair of coaxial idler gears 57 and 58, the smaller of which in turn drives gear 59 fixed to the end of drive shaft 34 to which indexing roller 32 is fixed, see Fig. 3. On the end of drive shaft 34 there is fixed a pulley 60 which is engaged by a spring belt 61 which drives pulley 62 fixed to stub shaft 63 journaled in a bearing 64 carried by one wall 65 of a sub-housing 66 fixed to the rear of the main housing 10, see Fig. 1. Also fixed to stub shaft 63 is a sprocket 67 which drives shaft 68 carrying metering roller 19 through a chain 69. If, for any reason, the supply of web to the metering roller 19 becomes fouled or jammed so that the metering roller 19 cannot feed the web to the loop L, then the spring belt

61 can slip on its pulleys 60 and 62 and the motor will not stall nor will sufficient pull be applied to the web W to tear the same.

The web W is fed along the top plate 15 by the indexing roller 32 to a chopping mechanism, indicated generally at 70, where the individual prints are chopped from the web. While this chopping mechanism may be of any known type, we have shown one comprising a stationary die block 71, the top of which is flush with the top of plate 15 and across which the web W is fed by the intermittent feeding means, see Figs. 1 and 2. Reciprocally mounted relative to this die block is a die carrier 72 connected to a U-shaped yoke 73 by a pair of bolts, only one of which is shown at 74. The die carrier 72 and yoke 73 are normally moved to a raised position by a plurality of springs 75, and in which position the die or knife carried by die carrier 72 is spaced from the die block so that the web W may be fed between the two. The die carrier is moved down against the die block to cut the web by oscillation of roller cams 76 disposed between the underside of the stationary die block and the top edge of the cross-arm of yoke 73, as clearly shown in Fig. 2. This roller cam comprises a circular bar 77 having a diametrical slot 78 at each end in which three balls 79 are rotatably disposed. This bar also has a flat portion 80 at each end and adjacent the slot 78 which allows the springs to drive the die block to a raised position. This position is shown in Fig. 2. When the roller cam is rocked clockwise from the position shown in Fig. 2 to a position wherein the balls 79 are vertically disposed, the yoke 73 is forced down against the action of springs 75 to bring the die carrier 72 down against the die block to cut the web.

Oscillation of the cams is intermittently and selectively accomplished by swinging actuating lever 81 back and forth through oscillation of bar 82 to one end of which lever 81 is connected by a sliding pivotal connection. The other end of lever 81 is eccentrically pivoted at 82' to the driven member 83 of a one-revolution clutch, indicated generally at 84, so that, as the clutch operates, the chopping mechanism is actuated and allowed to return to its normal inoperative position in which the die carrier is raised from the die block to permit a new length of web to be fed between the two by the intermittent mechanism. While any form of suitable one-revolution clutch can be utilized, we have shown one of a well-known type in which the driving member is a ratchet 85 fixed to the power shaft 53 to be continuously driven, and the driven member of the clutch comprises two similar plates 83 spaced from one another with the ratchet between them and each rotatably mounted relative to shaft 53. The driven plates 83 are positively connected to the ratchet when a semi-circular pawl 86, pivoted at one end to a stud 87 extending between plates 83 outside the periphery of the ratchet, swings inwardly and a tooth 88 thereon engages the ratchet. When the ratchet and pawl are in engagement, the driven plates 83 are positively connected to the driving ratchet. The pawl 86 is normally spring-pressed into engagement with the ratchet by a spring 89, and is held out of engagement with the ratchet when a release latch 90, pivoted at 91, engages a nose 92 on the pawl and positively holds the driven part of the clutch against movement. When release latch 90 is swung counterclockwise, looking at Fig. 3, and out of engagement with the nose 92 on the pawl, the pawl swings into operative engagement with the ratchet and the clutch starts to drive. A tension spring 93, connected between the pivot pin 82 and the frame of the apparatus, assists in starting the driven member the instant the pawl is released. Once the clutch starts to drive, the nose 92 of the pawl almost immediately passes out of the path of release latch 90 so that the latch can be allowed to return to its normal position wherein it will be in position to again engage the pawl after the clutch has made one revolution and thereby stop the clutch by disengaging the

pawl from the ratchet. A clutch of this general type is fully disclosed in U. S. Patent 1,987,742 to which reference can be had for a further description of the mechanical details thereof, but since the details of the clutch are not critical to the present invention, it is believed the general discussion thereof made above is sufficient to an understanding of this invention.

The release latch 90 constitutes one arm of a triple branch lever, a second arm 95 of which extends forwardly through an opening 96 in the front wall 13 of the housing 10 and terminates in a presser bar 97 which may be manually depressed to pivot the latch 90 to a clutch-actuating position, see Fig. 3, if it is desired to manually control the cutting mechanism as will be hereinafter described. In order to prevent the clutch from making more than one revolution should the operator accidentally hold the presser bar 97 down, a second release latch 94 is provided beside, and below, the main release latch which will be moved into the path of the nose 92 on the pawl when the release latch 90 is moved to a clutch-operating position. A tension spring 98 connected between the arm 95 and the underside of the top plate 15 normally moves the latch 90 to an operative position.

For automatic operation of the chopper, the third branch 99 of the triple branch lever is suitably connected with the plunger 100 of a solenoid or electro-magnet 101 which, when energized, pivots the latch 90 to a clutch-operating position. Thus, when the solenoid 101 is energized, the clutch 84 is engaged and drives the chopping mechanism to sever the length of web which has been fed through the chopping mechanism.

In moving between the indexing roller 32 and the chopping station, the web W passes over a detector or pick-up station comprising a pair of separated electrical contacts C and C' located in the surface of the top plate 15 in a position to be bridged and electrically connected by the conducting marks M spaced along the back of the web, see Fig. 1. These contacts may be mounted on a block 102 detachably connected to the top plate 15 and are connectable into a control circuit by lead wires 103 and 104. These contacts constitute an open switch in the control circuit of the apparatus and which switch is closed to complete the control circuit when a mark M on the web bridges the contacts during passage thereover. Closing of the control circuit causes a cessation of the intermittent feed and an operation of the chopping mechanism in the manner to be described hereinafter. The distance between the detector or pick-up station and the cutting plane of the chopper is equal to the distance between any mark on a print and the leading edge of said print, or the distance "x" shown in Fig. 7, so that the marks M control the accurate chopping of successive prints from the web W. To insure the marks M making good contact with each of contacts C and C' of the pick-up station, a roller 105 carried on the end of a pivoted arm 106, which is normally spring-pressed downwardly toward the top plate 15 by a spring 107, presses the web W down onto the contacts C, C' as the web passes this point.

Referring now to Fig. 8, the wiring diagram of the apparatus will be described. The power circuit, including leads 120 and 121, are taken off from a main source of 110 v. 60 cycle A. C. behind a single throw, double pole starting switch S. The driving motor 58 is connected directly into the circuit through branch leads 122 and 123 so that when the starting switch is closed the motor starts to drive the metering roller 19 and the indexing roller 32 through the drives therefor above described. The solenoid 101 for engaging clutch 84 which actuates the chopping mechanism is connected in a branch A. C. circuit 124 including a normally open switch 125. The solenoid 44 for stopping the intermittent feed and applying the brake to the web is preferably a D. C. solenoid 75 and is connected into a branch circuit 126 including a

selenium rectifier 119 which converts the current fed to this circuit into D. C. This branch circuit includes a normally open switch 127 so that the intermittent feed is normally operating. The switches 125 and 127 are both mechanically connected to the plunger 128 of a solenoid whose coil 129 is connected into a control circuit including a normally open switch 130.

This control circuit is connected into the main supply through a transformer 131 and a full wave rectifier tube 132 whose output includes a conventional π -section smoothing filter. A thyratron tube 133 is connected across this control circuit and its grid is connected to one side of the line through a dropping resistance 134 to insure the bias on the grid being sufficiently negative to insure normal cut-off. The coil 135 for closing switch 130 is connected in the anode circuit of tube 133 while the contacts C, C' of the detector or pick-up station constitute a normally open switch in the grid circuit of the tube, and connected into the circuit by leads 103 and 104 as before mentioned. Now when the contacts C, C' are not joined by a mark M on the back of the web, the tube 133 is not conducting and switch 130 remains open. This means switches 127 and 125 are open so that the intermittent feed operates to feed the web through the cutter when the same is in its normal inoperative position. Now when a mark M on the web passes the detector or pick-up station or connects contacts C, C' in the control circuit, this causes the control grid of the thyratron to assume a potential which will permit the tube to fire and conduct. The coil 135 is then energized to close switch 130 which in turn energizes coil 129 to close switches 125 and 127 which stops the paper drive and releases the single revolution clutch to drive the chopper.

In order to reset the control circuit after each chopping operation, a normally closed reset switch 136 is placed in the plate circuit of the thyratron to be momentarily opened by a cam 137 and thereby cut off the thyratron tube. The system is then prepared to receive the next conducting mark M and repeat the cycle. In order that the machine operate at its fastest possible speed, this switch should be opened the instant the die carrier of the cutter starts its upward stroke and is clear of the web path. Then the indexing of the web can be started during the time the die carrier is returning to its full raised position. To accomplish this, the switch 136 is mounted adjacent the clutch 84 and is arranged to be momentarily opened by a cam surface 137 fixed to the clutch plate 83 as it revolves, see Fig. 2. The mounting for the cam surface 137 is such that it permits adjustment thereof on the clutch plate, so that the switch 136 will be opened just about the time the die carrier starts its upward stroke. While we have shown the thyratron control circuit reset by a mechanically-operated switch, it is pointed out that the same result could be obtained electrically by using a relay having a time delay in place of coil 135 and switch 130 or by using a condenser and resistance network wired across the thyratron, the charging time of which would control the conducting time of the tube.

If, for any reason, the loop L in the web should become so small as not to contain a sufficient amount of web for a successive feeding operation, then the load on the intermittent feeding mechanism would become excessive and the length of web fed thereby might vary because the normal overtravel of the web due to this feed would not be the same as when being fed from a free loop. This will be appreciated when it is noted that this web may be fed past the pick-up station at a speed as high as 10. inches per second which means that after a mark M passes the contacts C, C' there is a certain overtravel of the web before the intermittent feed is stopped and the brake is applied. This overtravel is substantially constant when the web is being fed from a loop L which contains a length of web sufficient to supply the maximum feed encountered, and the spacing between the pick-up

station, or contacts C, C' and the chopper is adjusted to accommodate this overtravel.

Means is, therefore, provided to prevent operation of the intermittent feed should the loop L become too small. This means includes a normally open switch 138 connected in line 126 in parallel with normally open switch 127 and which is closed by energization of a solenoid whose coil 139 is in branch circuit 140 including normally open switch 141. This switch is adapted to be closed by a cam 142 when the loop L becomes too small, and when closed the solenoid 44 is kept energized to interrupt the intermittent feed and hold the rubber presser foot 43 in web-holding position. As best shown in Figs. 4 and 6, cam 142 is fixed to a sleeve 143 rotatably mounted on a stub shaft 144 supported by bracket 145. To the end of this sleeve is fixed one end of a feeler arm 146 which includes a cross bar 147 on its other end which extends across the web path. A spring 148 normally moves said feeler arm 146 in an upward direction so that the cross bar 147 thereof, which engages the underside of the loop L, normally follows the loop as it increases in size. The switch 141 is mounted adjacent cam 142 and has a roller 149 on the end of its actuating arm which normally rides on the periphery of cam 142. When the loop L becomes too small, as shown in full lines in Fig. 6, the feeler arm 146 is pulled down so that the high portion of cam 142 engages the actuating arm of the switch 141 to close the same. This paralyzes the intermittent feed until the loop L regains its normal size, due to the continued operation of metering roller 19, whereupon feeler arm 146 is allowed to rise under the action of its spring 148 and reopen switch 141 so that the solenoid 44 is de-energized and the intermittent feed is set in motion.

Should the loop L become too large, which might indicate a jamming of the web in front of the chopper, or should it disappear completely, which would happen if the supply of web becomes exhausted or the web breaks in its approach to the intermittent feed, it is desirable that the entire feed of the apparatus be paralyzed. To this end, a normally closed switch 150 is connected in the circuit of the motor 50 to be opened by a cam 151 when the loop L becomes too large or disappears, see Fig. 8. As shown in Figs. 4, 5 and 6, this cam 151 is fixed on sleeve 143 beside, and coaxially with, cam 142 and its periphery is engaged by a roller on the actuating arm of switch 150, also mounted beside switch 141. Thus, when the loop L is any size, other than too large, the low portion of cam 151 allows switch 150 to remain closed so that the metering roll 19 continues to feed web to the loop, see full-line position of feeler arm in Figs. 5 and 6. However, should the loop L become too large or disappear, the feeler arm moves upward to the dotted-line position shown in Fig. 6, whereupon the high position of cam 151 engages the roller on the switch-actuating arm and opens switch 150 to cut the power off from the motor 50.

Should it be desired to feed the web W by hand, the guide bar 25 is raised to the vertical position shown in dotted lines in Fig. 5, and in which position it is frictionally held by spring-pressed ball 27 engaging notch 29 in its arm 26. When moved to this position, the guide bar carries the feeler arm 146 with it because cross bar 147 thereof overhangs arm 26. This causes sleeve 143 to be rotated to a position wherein the cam 142 closes switch 141 to keep the intermittent feed inoperative, while cam 151 opens switch 150. For manual operation, switch 152 is manually closed to short switch 150 and keep the motor operating to drive the chopping mechanism upon manual operation of the clutch 84 by presser bar 97. By the same operation, or a separate one, the control circuit is paralyzed by manually opening normally closed switch 153 in the plate circuit of the thyratron 133. The rubber presser foot 43 and the pressure roller 39 are moved away from the web path for threading or manual feeding of the web by gripping hand lever 154 and swinging it clockwise whereupon crank arm 42 is rotated to raise the eccentric

41 away from the web path. When the web is fed to the chopper manually the signals M on the web are not used to control the chopper action, but the clear areas A between the prints P or the leading edge of the prints are aligned with an index mark over a translucent portion in the top plate 15 which is lighted by a lamp from below, by means not shown. As the prints are chopped from the web, they are pulled from the chopper and fed into a hopper, not shown, by constantly-driven rubber-covered roll 155 engaged by free running rollers 156. Rolls 155 are driven through a belt and pulley combination 157 driven by motor 50 by means not shown.

Having thus described our invention, what we claim is new and desire to secure by Letters Patent of the United States is:

1. In an apparatus for severing a continuous web of material into sheets of given lengths in accordance with signal marks spaced along the length of said web, the combination with a normally inoperative cutter; a primary strip-feeding means for constantly feeding the web into a free loop and toward said cutter; a secondary strip-feeding means for intermittently feeding said web from said loop over a given path to said cutter and including a member movable to and from an operative position wherein it engages and feeds said web; a brake for said web immediately in front of said secondary feeding means and movable to and from an operative position wherein it is adapted to hold said web at the forward end of said loop when said secondary feeding means is not operating to advance the web; electrically actuated means for moving said member of the secondary feeding means from its operative position, said brake to its operative position and for actuating said cutter substantially simultaneously, and a power circuit for energizing said electrically actuated means and including a normally open electrical switch disposed in said path of said web and adapted to be closed when one of said signal marks on said web pass across the same, and means for returning said secondary feeding means to its operative position and said brake to its inoperative position when the cutter completes a severing operation.

2. An apparatus for severing a continuous web of material according to claim 1, and including means controlled by said loop in the web for moving said member of the secondary feeding means from its operative feeding position and for moving said brake to its operative position when said loop becomes reduced below a given size.

3. An apparatus for severing a continuous web of material according to claim 1, and including means controlled by said loop in the web for moving said member of the secondary feeding means from its operative feeding position and for moving said brake to its operative position when said loop becomes reduced below a given size, and means also controlled by said loop for stopping said primary feeding means when said loop becomes larger than a given size or becomes nonexistent by virtue of the web breaking or becoming used up.

4. In an apparatus for severing a continuous web of material into sheets of given lengths in accordance with signal marks spaced along the length of said web, the combination with a normally inoperative cutter; a primary strip feeding means for constantly feeding the web into a free loop and toward said cutter; means for intermittently feeding said web from said loop over a given path and past said cutter, and including a continuously rotating friction roll across the top of which said web passes, a presser roll above said friction roll and web pivoted to swing between a normal operative position, wherein it presses the web into driving engagement with said friction roll, and an inoperative position, wherein it is spaced from said friction roll by a distance greater than the thickness of the web; a solenoid for moving said presser roll to, and holding it in, the inoperative position when energized, a brake for said web movable between an operative position, wherein it frictionally engages the

web between the loop and said intermittent feeding means and holds the web against movement toward said intermittent feeding means, and a normal inoperative position, wherein it is freed from engagement with said web, a second solenoid for moving said brake to, and holding it in, its operative position when energized, a power circuit containing both of said solenoids and including a normally open switch; means responsive to one of said signal marks on said web passing a given point in said path for closing said switch and causing said solenoids to be energized to stop the feed of the web to the cutter and to apply the brake to the web at the forward end of said loop; means for operating said cutter when the web is stopped therebeneath, and means for reopening said power circuit after the cutter has severed the web.

5. In an apparatus for severing a continuous web of material into sheets of given lengths in accordance with signal marks spaced along the length of said web, the combination with a normally inoperative cutter; a primary strip-feeding means for constantly feeding the web into a free loop; means for intermittently feeding said web from said loop over a given path including a stationary surface and past said cutter, and including a continuously rotating friction roll across the top of which said web passes; a presser roll above said friction roll and web pivoted to swing between a normal operative position, wherein it presses the web into driving engagement with said friction roll, and an inoperative position, wherein it is spaced from said friction roll by a distance greater than the thickness of the web; a friction pad movable between an operative braking position, wherein it moves down on top of said web and presses it against said stationary surface ahead of said friction roll, and an inoperative position, wherein it is spaced from said web; a double ended lever pivoted intermediate its ends on an axis parallel to and extending transversely of said web, said presser roll and said friction pad mounted on opposite ends of said lever; a spring acting on one end of said lever to swing the presser roll to its operative position and the friction pad away from the web; a solenoid acting on the other end of said lever to move the friction pad into engagement with the web and to raise the presser roll when energized; a power circuit containing said solenoid and including a normally open switch; means responsive to one of said signal marks on the web passing a given point in said path for closing said switch and causing said solenoid to be energized to stop the feed of the web to the cutter and to apply the brake to the web at the forward end of the loop; means for operating said cutter when the web is stopped therebeneath, and means for reopening said power circuit after the cutter has severed the web.

6. In an apparatus for severing a continuous web of material into sheets of given lengths in accordance with signal marks spaced along the length of said web the combination with a normally inoperative cutter; means for selectively driving said cutter through a single cutting stroke, including a single revolution clutch, an electromagnet for actuating said clutch; means for continuously feeding the web into a loop and toward the cutter; a motor for driving said feeding means; means for intermittently feeding said web from the loop over a given path and past said cutter and for holding said web from moving beyond said loop when not being fed and including a rubber-covered feeding roll lying beneath the web and connected to said motor to be continuously driven thereby; a presser roller disposed above said web and movable between an operative position, wherein it presses the web into driving engagement with said feeding roll, and an inoperative position, wherein it is lifted from said feeding roll; a stationary surface across which said web is fed; a rubber brake member movable between an operative position, wherein it presses said web against said stationary surface to frictionally grip the same, and an inoper-

ative position, wherein it is raised from said web, said presser roller and brake member carried on opposite ends of a lever pivoted intermediate its ends so that when said lever is pivoted in one direction the presser roller is moved to its inoperative position and the brake member is moved to its operative position and vice versa; means normally moving said lever to a position to move said brake member to an inoperative position and operate said intermittent feed, a solenoid for moving said lever to its other position; a power circuit including said solenoid and electro-magnet; a normally open switch in said power circuit; means for closing said switch including a control circuit having a normally open switch adapted to be closed by passage of said signal marks on the web past a given point in said given path.

7. In an apparatus for severing a continuous web of material into sheets of given lengths in accordance with signal marks spaced along the length of said web, the combination with a normally inoperative cutter; means for selectively driving said cutter through a single cutting stroke, including a single revolution clutch, an electromagnet for actuating said clutch; means for continuously feeding the web into a loop and toward the cutter; a motor for driving said feeding means; means for intermittently feeding said web from the loop over a given path and past said cutter and for holding said web from moving beyond said loop when not being fed and including a rubber-covered feeding roll lying beneath the web and connected to said motor to be continuously driven thereby; a presser roller disposed above said web and movable between an operative position, wherein it presses the web into driving engagement with said feeding roll, and an inoperative position, wherein it is lifted from said feeding roll; a stationary surface across which said web is fed; a rubber brake member movable between an operative position, wherein it presses said web against said stationary surface to frictionally grip the same, and an inoperative position, wherein it is raised from said web, said presser roller and brake member carried on opposite ends of a lever pivoted intermediate its ends so that when said lever is pivoted in one direction the presser roller is moved to its inoperative position and the brake member is moved to its operative position and vice versa; means normally moving said lever to a position to release said brake member and initiate said intermittent feed, a solenoid for moving said lever to its other position; a power circuit including said solenoid and electro-magnet; a normally open switch in said power circuit; means for closing said switch including a control circuit having a normally open switch adapted to be closed by passage of said signal marks on the web past a given point in said given path, and means for resetting said power circuit by opening the normally open switch therein as soon as said cutter chops said web.

8. In an apparatus for severing a continuous web of material into sheets of given lengths in accordance with signal marks spaced along the length of said web, the combination with a normally inoperative cutter; means for selectively driving said cutter through a single cutting stroke, including a single revolution clutch, an electromagnet for actuating said clutch; means for continuously feeding the web into a loop and toward the cutter; a motor for driving said feeding means; means for intermittently feeding said web from the loop over a given path and past said cutter and for holding said web from moving beyond said loop when not being fed and including a rubber-covered feeding roll lying beneath the web and connected to said motor to be continuously driven thereby; a presser roller disposed above said web and movable between an operative position, wherein it presses the web into driving engagement with said feeding roll, and an inoperative position, wherein it is lifted from said feeding roll; a stationary surface across which said web is fed; a rubber brake member movable between an operative position, wherein it presses said web against

said stationary surface to frictionally grip the same, and an inoperative position, wherein it is raised from said web, said presser roller and brake member carried on opposite ends of a lever pivoted intermediate its ends so that when said lever is pivoted in one direction the presser roller is moved to its inoperative position and the brake member is moved to its operative position and vice versa; means normally moving said lever to a position to release said brake member and initiate said intermittent feed, a solenoid for moving said lever to its other position; a power circuit including said solenoid and electro-magnet; a normally open switch in said power circuit; means for closing said switch including a control circuit having a normally open switch adapted to be closed by passage of said signal marks on the web past a given point in said given path, and means for energizing said solenoid when said loop becomes reduced below a given size, and including a second normally open switch in said power circuit connected in parallel with said first normally open switch; and means controlled by the size of said loop for closing said second switch and maintaining it closed until said loop reaches a given minimum size.

9. In an apparatus for severing a continuous web of material into sheets of given lengths in accordance with signal marks spaced along the length of said web, the combination with a normally inoperative cutter; means for selectively driving said cutter through a single cutting stroke, including a single revolution clutch, an electromagnet for actuating said clutch; means for continuously feeding the web into a loop and toward the cutter; a motor for driving said feeding means; means for intermittently feeding said web from the loop over a given path and past said cutter and for holding said web from moving beyond said loop when not being fed and including a rubber-covered feeding roll lying beneath the web and connected to said motor to be continuously driven thereby; a presser roller disposed above said web and movable between an operative position, wherein it presses the web into driving engagement with said feeding roll, and an inoperative position, wherein it is lifted from said feeding roll; a stationary surface across which said web is fed; a rubber brake member movable between an operative position, wherein it presses said web against said stationary surface to frictionally grip the same, and an inoperative position, wherein it is raised from said web, said presser roller and brake member carried on opposite ends of a lever pivoted intermediate its ends so that when said lever is pivoted in one direction the presser roller is moved to its inoperative position and the brake member is moved to its operative position and vice versa; means normally moving said lever to a position to release said brake member and initiate said intermittent feed, a solenoid from moving said lever to its other position; a power circuit including said solenoid and electro-magnet; a normally open switch in said power circuit; means for closing said switch including a control circuit having a normally open switch adapted to be closed by passage of said signal marks on the web past a given point in said given path, and means for energizing said solenoid when said loop becomes reduced below a given size, and including a second normally open switch in said power circuit connected in parallel with said first normally open switch; and means controlled by the size of said loop for closing said second switch and maintaining it closed until said loop reaches a given minimum size, and means controlled by the size of said loop for stopping said constantly-driven feeding means when the loop becomes too large, and including a normally closed switch in that portion of the power circuit including said motor, and means controlled by enlargement of said loop beyond a given size for opening said normally closed switch.

10. An apparatus for severing a continuous web of material into sheets according to claim 9, in which the means for closing said second normally open switch and opening said normally closed switch includes a pair of

15

cams, and a feeler arm including a portion engaging said loop and normally spring-pressed in a direction to follow said loop and be moved in response to a change in size of said loop, said feeler arm mechanically connected to said cams to oscillate the same as the arm moves.
